(57) **CLAIM**

I claim the ornamental design for a ball cap for a bicycle cable, substantially as shown and described.

DESCRIPTION

FIG. 1 is an isometric view of ball cap for a bicycle cable, showing my new design;

FIG. 2 is a front view thereof;

FIG. 3 is a back view thereof;

FIG. 4 is a left side view thereof;

FIG. 5 is right side view thereof;

FIG. 6 is a top view thereof;

FIG. 7 is a bottom thereof;

FIG. 8 is an exploded view thereof showing a set screw exploded away from the set screw opening in the ball cap; and,

FIG. 9 is an isometric view thereof showing a bicycle cable in dotted lines.

The broken lines shown in FIG. 9, illustrates environment that form no part of the claimed design.

1 Claim, 3 Drawing Sheets
